CLAIM

I claim, the ornamental design for a communicator, as shown and described.

DESCRIPTIONFIG. 1 is a perspective view, showing our new design;
FIG. 2 is a front elevational view thereof;

FIG. 3 is a rear view thereof;

FIG. 4 is a right side view thereof;

FIG. 5 is a left side view thereof;

FIG. 6 is a top plan view thereof; and,

FIG. 7 is a bottom plan view thereof.

The broken lines in the drawings depict portions of the communicator that form no part of the claimed design.

1 Claim, 7 Drawing Sheets(56)
